CLOTHES DRIER

Filed Oct. 6, 1930

UNITED STATES PATENT OFFICE

MACK DURYEE, OF BAY CITY, MICHIGAN

CLOTHES DRIER

Application filed October 6, 1930. Serial No. 486,649.

This invention relates to an improved clothes drier, and more particularly to an adjustable drier, which is adjustable vertically so that it can be readily lowered to permit clothes to be easily placed thereon, after which the reel may be raised, eliminating any possibility of the clothes dragging on the ground as the reel revolves, and so that full advantage may be taken of stronger air currents which prevail at higher stratus.

Another object of the invention is to provide a simple, practical, and economical clothes drier provided with a bearing, so that the reel rotates with a minimum of friction, and is actuated by very gentle air currents.

A further object is to provide simple and easily operable means for raising the reel, and also provide means for holding it in adjusted position.

The above and other objects will appear as the specification progresses, reference being had to the accompanying drawings in which I have shown the preferred embodiment of my invention, and in which like reference numerals indicate like parts throughout the several views thereof.

In the drawings.

Fig. 1 is a view showing my improved clothes drier in side elevation, the dotted lines showing the reel in raised position.

Fig. 2 is a fragmentary plan view.

Fig. 3 is an enlarged fragmentary sectional view showing the head and bearing construction.

Fig. 4 is a transverse sectional plan through the standard.

Fig. 5 is a fragmentary enlarged detail showing the ratchet wheel and ratchet.

Fig. 6 is an enlarged detail showing the manner of connecting the hanger bars.

Fig. 7 is a view similar to Fig. 3, showing a slightly different head construction.

Referring now more particularly to the drawings in which I have shown the preferred embodiment of my invention, the numeral 5 indicates a base on which a vertically disposed pipe standard 6 is mounted, said standard being provided with an elongated

slotted opening 7 for a purpose to be presently described.

A telescoping pipe section 8 is slidably mounted in the standard 6, and a laterally projecting lug 9 is anchored therein, and projects through the elongated opening 7 in the standard. A substantially U-shaped frame "B" fits over the upper end of the standard, and an anti-friction bearing 10 is interposed between the upper end of the standard and the frame, and to which it is secured in any approved manner, a collar 11 is slidably mounted on said standard and the lower end of the frame is rigidly secured thereto by means of rivets 12.

A similar collar 13 is spaced from the collar 11, and vertically disposed bars 14 are secured thereto, the ends 15 being turned at right angles to the main body, and arms 16 are secured to the lower end of said bars, the inner ends of said arms being split as clearly shown at 17 in Fig. 5, to accommodate the end 15 of the bar 14, a rivet 18 serving to secure the parts together.

Stays 19 are connected to the upper end of the bars 14, the opposite end being anchored to the arms 15 as shown at 20, a plurality of lines 21, (formed of cable or flexible rope) being stretched between said arms and on which the clothes are hung.

Side bars 22 are secured to the standard 6 by means of bolts 23, and a transversely disposed shaft 24 is journaled therein, a winding drum 25 being keyed on said shaft, and one end of a cable member 26 is secured thereto, the opposite end of said cable being anchored to the lug 9 as shown.

A toothed ratchet wheel 27 is also secured on the shaft 24, and a ratchet 28 is pivotally mounted on one of said side bars, and is adapted to engage said ratchet wheel for locking it in set position.

In Fig. 7 of the drawings, I have shown a slightly different head construction, this includes a preferably hard wood block 29 secured to the frame "B" in any approved manner, a socket 30 being formed in the face thereof and a round headed bolt 31 is provided in the end of the sleeve 8 and when this head and socket is preferably lubricated, it 100

makes a very simple and practical bearing, which due to its simplicity, is preferable to the construction shown in Fig. 3.

The reel is adjusted by means of a crank 29 which is secured on the end of the shaft 24, and when it is desired to raise or lower the reel, the crank is actuated so that the cable 26 is wound on the drum, and the telescoping section 8 is raised accordingly. The bearing 10 insures ease of operation, and the reel structure is light and can be easily raised and operated.

From the foregoing description it will be obvious that I have perfected a very simple, substantial, and easy operating clothes drier.

What I claim is:

1. In a clothes drier, a standard having inner and outer telescoping sections, a collar slidably mounted on said standard, a U-shaped frame secured to said collar, and an antifriction bearing interposed between the top of said standard and the frame.
2. In a clothes drier, a telescoping pipe standard, a clothes reel frame revolvably mounted on said standard, and including an antifriction bearing interposed between the top of the standard and the clothes reel frame, and means for adjusting the height of the clothes reel frame.
3. In a clothes drier, a telescoping standard comprising inner and outer telescoping sections, a reel frame mounted thereon and including a U-shaped frame, an antifriction bearing interposed between the top of the standard and the said frame, a winding drum mounted on the outer section of the standard, and a cable anchored to the inner section of said standard and adapted to raise the inner section and reel frame when the drum is rotated.
4. In a clothes drier, a telescoping standard including an inner sleeve member, a reel frame mounted on the standard and comprising spaced apart collar members to which said reel frame is secured, an antifriction bearing interposed between the top of the standard and the reel frame, a drum mounted on said standard and having a cable anchored thereto, the opposite end of the cable being anchored to the inner sleeve, and angularly disposed members for bracing the arms of the reel frame.

In testimony whereof I affix my signature.
MACK DURYEE.
